UNITED STATES PATENT OFFICE.

RICHARD S. ARTHUR, OF NEWARK, NEW JERSEY, ASSIGNOR, BY MESNE ASSIGNMENTS, TO UTILITY CABINET COMPANY, OF NEWARK, NEW JERSEY, A CORPORATION OF NEW JERSEY.

VENDING MACHINE.

Application filed September 18, 1919. Serial No. 324,353.

To all whom it may concern:

Be it known that I, RICHARD S. ARTHUR, a citizen of the United States, and a resident of Newark, in the county of Essex, and State 5 of New Jersey, have invented certain new and useful Improvements in Vending Machines, of which the following is a full, clear, and exact description.

Among the principal objects which the 10 present invention has in view are: To furnish a multiple unit machine in which the operation of each unit is independent of other units; to provide a machine of the character mentioned, in which the units are 15 arranged in groups that may be multiplied; to prevent attempts to operate any of the units after the same have been once employed; to lock the units universally; to simplify the operation of clearing the 20 mechanism of foreign substance, easy and readily effected; to display the articles to be vended favorably; and to simplify the construction of the machine.

Drawings.

Figure 1 is a front elevation of a machine, constructed and arranged in accordance with the present invention showing two operating units and the key for unlocking the same.

30 Figure 2 is a vertical section, the section being taken as on the line 2—2 in Fig. 1.

Figure 3 is a detail view showing one of the locking mechanisms detached from the machine, and in its inactive position, the 35 broken lines being used to show a deposited coin or token therein.

Figure 4 is a rear elevation of the same.

Figure 5 is a longitudinal section, the section being taken as on the line 5—5 in Fig. 40 6.

Figure 6 is a vertical section, the section being taken as on the line 6—6 in Fig. 1.

Figure 7 is a view similar to Fig. 3, the 45 parts of the mechanism being shown in their active position.

Figure 8 is a rear elevation, partly in section, of a portion of the mechanism and the container for the goods being vended, the section is taken as on line 8—8 in Fig. 6.

50 Figure 9 is a horizontal section of the con-

tainier for an article being vended, the section being taken as on the line 9—9 in Fig. 8.

Figure 10 is a horizontal section showing the locking mechanism of the machine, the section being taken as on the line 10—10 in 55 Fig. 1.

Figure 11 is a detail view showing in section the universal locking bar, the section being taken as on the line 11—11 in Fig. 10.

Figure 12 is a detail view showing in section the guide key with which the locking bar is provided.

Figure 13 is a detail view showing the means by which the key is held in operative position until the locking bar is locked.

Description.

As seen in the drawings the present machine is particularly adapted for vending articles which are placed in containers and subsequently automatically released for delivery therefrom. The special use to which the machines are put at present is that of supplying hotels and similar institutions with articles of toilet, such as face cream, 70 tooth brushes and such. The articles mentioned are such as are often overlooked by the travellers when packing on the eve of a journey.

The containers in which the various articles are placed when once opened should not be refilled until the money which has been deposited in the machine in purchase, has been removed therefrom. To this end, each of the locking mechanisms with which each 85 container is associated, is arranged to retain its coin until the attendant replenishes the container. This attendant obviously, is connected in some way with the proprietor of the machines, and is responsible for the 90 moneys taken therefrom. To this end, a series of containers 20 are pivotally mounted in a case having a top partition 21, and a bottom partition 22. The containers 20 are preferably cylindrical and adapted for receiving the usual square package in which face and shaving creams and articles of a like character are purveyed. Each cylinder has at the upper end thereof, a pintle 23. Around each pintle is wrapped a coil spring 100

24. Two openings are formed in each of the containers, one of which forms a window provided with a transparent pane 25. Normally this window and pane 25 are turned 5 to the front of the machine when the container holds an article to be sold. The rear opening 26 is sufficiently large to permit the introduction of the said article.

A relatively long spring loop 27 is placed 10 in each of the receptacles so that the article being offered will be pressed toward the window and pane 25 thereof. In this way the cabinet or assembled containers is given a neater appearance.

15. Each of the various containers is normally locked in closed position. They cannot be re-locked in closed position after the contents have been removed therefrom until the money received therefor has been 20 taken from the machine or from the locking mechanism with which the container in question is associated. The means by which this is accomplished disclosed best in Fig. 8 of the drawings as a spring operated 25 latch 28.

The latch 28 has a pivot 29 extending between the walls of a housing 30 therefor. The spring 31 with which each latch is associated is a loop, the free ends of which 30 extend outside of the container.

In the closed or active position of the containers, each latch 28 engages a nich 32 formed in the upper edge of the locking mechanism with which the particular 35 container is associated. Each locking mechanism is associated with one of the various containers and operates to secure and release only the container with which it is associated. These locking mechanisms operate to, first release the container for permitting the spring 24 to rotate the container, so that the opening 26 is turned to the front to permit the purchaser to extract the article held in the container. The locking 40 mechanism retains the token or coin with which it is operated, and is itself locked in closed position by a universal or master-lock of the machine, as more fully explained.

45. As shown best in Fig. 2 of the drawings, each of the locks is pivotally suspended by means of pins 33 in lugs raised from the upper partitions 21 of the case holding the containers.

50. As seen best in Fig. 1 of the drawings, a hinge is formed by overturning the upper extremity of the face plate 34 of each of the locks. In the normal closed position of the locks, the face plates 34 are held vertically, said face plates filling the space between the containers 20. Each face plate 55 has a coin slot 35, through which the coin representing the price of the articles to be purchased is introduced into the lock. Adjacent the lower end of each face plate

34, are slots forming passages for the side 65 bars 36 of each of the push-plungers 37.

As seen best in Fig. 7, the members 36 straddle the rectangular coin chute 38. The interior dimension of the chute 38 approximates the width of the opening 35, in the 70 face plate 34. Through horizontally disposed passages 39, extends a pin 40. The pin 40 co-operates with a block 41 to arrest and support the coin 42, or a token used in lieu thereof, in its delivered position.

75. As shown best in Fig. 2, the block 41 has an upwardly inclined surface which leads to the sill 43 at the delivery end of the block 41. The sill 43 co-operates with a plunger 44, to lift the releasing lever 45, the said lever being lifted by the coin 42 just sufficiently to free the latch 28 from its engagement by the nich 32 with which it is associated. Re-adjustment of the sill 43 and of the plunger 44 may be refined to 80 such an extent that any article having a slight fraction less than the diameter of the coin designed to operate the machine, would fail to lift the lever 45 sufficiently to 85 release the latch 28, and so fail to operate 90 the machine.

95. It has been explained above how, when the latch 28 is lifted from the nich 32, the spring 24 rotates the container 20, to expose the opening 26 to the end that the article sold may be removed from the container. It will be noted that when the lever 45 is rocked on the pin 46, a trigger end 47, with which it is provided, is introduced in line with the passage or coin slot 35, the object being to prevent the introduction of a second coin prior to the removal of the first coin 42. By this method the operator of the machine is safeguarded against introducing a coin which would fail to operate 105 the machine in the event that a bogus token, or so-called slug has been introduced, and which, by reason of its failure to correspond exactly with the size of the coin, had failed to release the container.

110. Normally, the plunger 44 is held in its lowered or inactive position by a pull spring 48. The operative connection between the plunger 44 and the lever 45 is formed by a circular socket 49 in the plunger 44 and a disk-like knuckle 50 at the end of the lever 45. A similar office is performed for the side bars 36 by a spring 51, which normally operates to rock the side bars 36 on the pins 46, until the pin 40 connecting the said side bars 36 rest against the face plate 34.

115. To avoid the chutes 38 becoming clogged, the said chutes are provided with, vertically disposed slots 52. As seen best in Figs. 2 120 and 3 of the drawings, the said slots are so disposed that should the chutes become congested or clogged with some foreign ma-

terial, accidentally or maliciously, it may be removed by forcing the same down to the lower or delivery end of the said chutes.

After being moved by the plunger 37 and side bars 36 to release the container, the coin 42 is held in the position shown in Fig. 7, until manually extracted therefrom by the attendant. To do this the chutes and parts associated therewith, are swung on the pin 38 outwardly until the coin is exposed so as to be removed from the chute. Before doing this, however, it is necessary to release the chute from engagement with one of the locking dogs 53. There is one dog to each of the chutes 38. Each dog has a pivot pin 54 and a supporting spring 55 by which it is normally raised so that the head of each dog enters a recess 56 with which each chute, and the block 41 thereof, is provided. After the plunger 37 and parts associated therewith have moved the coin 42 to the position shown in Fig. 7, the spring 51 returns the plunger to its normal position, the coin 42 being held in the position shown in Fig. 7 by the plunger 44 and the spring 48 connected therewith, the end of the said plunger resting on the center of the coin 42.

All of the latches 53 are depressed by rotating a locking rod 57. As seen best in Fig. 10 of the drawings, the rod 57 extends lengthwise of the machine, and is provided at intervals, with flat portions 58. Each flat portion 58 rests over one of the latches 53. When the rod 57 is turned to the position shown in Fig. 2 of the drawings, it will be observed that the flattened portions 58 permit the springs 55 to lift the latches 53 to engage the recesses 56 of the chutes 38. Whenever the rod 57 is turned to the position shown in Fig. 10 of the drawings, it is evident that all of the latches 53 are depressed, releasing all of the chutes 38, thereby permitting any one or all of them to be swung on their pintles 33. The coins, if any have been deposited, may then be removed.

The rod 57 is rotated by means of a key 59. The key 59 is of any suitable manufacture and is preferably a key difficult to imitate, and of what is known as the "master" type. The key has an extension 60, which passes through a recess 61 besides the key-hole in the frame of the machine. The movement of the key 59 to rock the rod 57 carries the extension 60 beyond the recess 61 and prevents the withdrawal of the key. The key has to be moved so that the extension 60 corresponds with the nich 61, and in that position of the key, the rod 57 is placed in a position where all of the latches 53 are in operative or engaging position. By this means is avoided the failure of the attendant to lock the machine while withdrawing the key.

These machines are usually attached to the wall of a standing structure. In the present machine, the method of attaching the machine is to fasten it to the wall by means of the screws such as indicated in Fig. 2 of the drawings, by the numeral 62. Holes 70 are provided in the back of the machine casting and in line with the chutes 38, it being necessary to swing outward one of the chutes to expose the screws 62.

It will be observed that after the machine has been operated so that any one or more of the containers have been released, the said retainers cannot be returned to what may be termed the "full" position and be held there until after the coin, which has previously operated it, has been removed. Therefore the receptacles cannot be refilled by meddlers and returned to what seemingly is the operative position, as the attendant on the machine is the only one that can use the key 59 for the purpose of releasing the chute which holds the coins so that they may be removed for relocking the containers in normal position.

The latch 28 is guided by the cam 64 when entering the nich 32. When the container 20 is released, and springs in the opposite direction, the latch 28 is prevented from interfering with the similar latch of the next mechanism by the cam 65, which is provided for each of the locking mechanisms. It will be noted particularly in Fig. 3 that the riding surface of the cam 65 extends above the riding surface of the cam 64.

It will be understood that these machines are generally made up in what may be termed "operative" units having four or five containers in a bank, each receptacle being associated with one of the coin chutes. When a greater number of containers are desired in any installation, this is secured by having two banks, one above the other, the upper one being secured to the lower by suitable fastening devices which are passed through the bottom of the upper bank, and the top of the lower bank. These fastening devices are held within the casings, and therefore cannot be meddled with and the machine or portion thereof, cannot be removed from its installation.

To prevent tampering with the coin held in any of the chutes and locking mechanisms associated therewith, and to form a guide for the latches 53, I provide cheek plates 63. The plates 63 as seen best in Figures 2, 6 and 10 of the drawings, are spaced apart to receive the sides of the chute 38 and the coin 42 held therein. The plates 63 extend above the coins 42 when held in the position shown in Fig. 7. This effectively prevents the introduction of any instrument through a partially opened space covered by the receptacles 20 when released and so prevents the

malicious withdrawal of the coin after the receptacle has been delivered of its contents.

Claim.

5. A machine as characterized having a plurality of containers, each having a delivery opening normally closed; a plurality of single service unlocking mechanisms, each operatively related to one of said containers

for releasing the same, said mechanisms being operable by a device surrendered to said mechanism for retention thereby until manually extracted therefrom; and means for preventing the locking of said containers in closed relation prior to the extraction of the device from the unlocking mechanisms. ¹⁰

RICHARD S. ARTHUR.
